SPOON OR SIMILAR ARTICLE OF FLATWARE

John P. Young, Bronxville, N. Y., and Charles A. Arnold, Providence, R. I., assignors to Lyon Incorporated, Detroit, Mich., a corporation of Delaware

Application July 13, 1955, Serial No. 36,964

Term of patent 14 years

(Cl. D54—12)

Fig. 1

Fig. 2

Fig. 3

Fig. 1 is a plan view of a spoon or similar article of flatware, showing our novel design;

Fig. 2 is a side or profile view showing the contour of our novel design of Fig. 1; and

Fig. 3 is a rear view thereof.

The essential features of our design reside in the handle portion shown in full lines on the drawing.

We claim:

The ornamental design for a spoon or similar article of flatware, substantially as shown and described.
